UNITED STATES PATENT OFFICE.

HARRIS HANFLIG, OF CHARLESTOWN, MASSACHUSETTS.

COMBINATION-LOCK.

976,872.

Specification of Letters Patent. Patented Nov. 29, 1910.

Application filed October 15, 1909. Serial No. 522,735.

To all whom it may concern:

Be it known that I, HARRIS HANFLIG, a citizen of the United States, residing at Charlestown, in the county of Suffolk and 5 State of Massachusetts, have invented a new and useful Improvement in Combination-Locks, of which the following is a specification.

This invention relates to combination locks, the object being to provide a combination lock which is exceedingly simple and cheap in construction and one which is so constructed that the same is especially adapted to be used on trunks and the like. 10 Another object of my invention is to provide a lock which is provided with a pair of parallel shafts on which are mounted dial operated tumblers co-acting with a sliding bolt member whereby it will be necessary 15 for all of the tumblers to be brought into alinement before the bolt can be operated.

A further object of my invention is to provide novel means for securing the dial wheels upon the tumblers so that the same 20 can be readily shifted in order to change the combination.

A still further object of the invention is to provide a lock which is so constructed that the same can be used upon a door as 25 well as a trunk and the dial wheels are so mounted that they can be easily operated from the inside or outside.

Still another object of my invention is to provide novel means for securing the shafts 30 in position in the casing whereby they can be readily detached.

With these various objects in view, my invention consists in the novel features of construction, arrangement and combination of 35 parts, all of which will be described fully hereinafter and pointed out in the claims.

In the drawing forming a part of this specification: Figure 1 is a front elevation of my improved lock. Fig. 2 is a top plan view with the face plate removed. Fig. 3 is a section taken on the line 3—3 of Fig. 2. Fig. 4 is a section taken on the line 4—4 of Fig. 1. Fig. 5 is an inverted plan view of a face plate removed showing the bolt member. Fig. 6 is a bottom plan view of the lock. Fig. 7 is a section taken on the line 7—7 of Fig. 2.

In carrying out my improved invention, I employ a casing A provided with dove-tailed vertical grooves A' in its ends in 55 which are mounted dove-tailed shaped sup-

porting blocks B provided with oval shaped recesses in their faces as clearly shown at B' in Figs. 7 in which are adapted to fit the similarly shaped ends C' of shafts C which are provided with shoulders C² formed by reducing the ends as shown at C³ on which are loosely mounted notched tumblers D which are provided with disk portions D' having their peripheries toothed as shown at D² over which are adapted to be placed dial rings E which are correspondingly toothed as shown at E' so that the same can be readily removed or placed in position on the disk in order to change the combination of the lock as will be hereinafter fully described. These dials extend through slots A³ formed in the bottom of the casing A so that they can be readily operated from the inside when the casing is in position in a door or trunk. The shafts are provided with plates F one of which engages the bottom and the other the top for preventing the shaft from rotating when the tumblers are operated.

Mounted on the casing A is a face plate G which is provided with slots G' to receive the dials E and the plate is also provided with marks G² so as to indicate the correct position of the letters on the dial in order that the combination can be worked, and it will be seen that by operating the dial wheel so as to cause the respective tumblers of each shaft to be turned into alinement, the tumblers will be in such a position that the lock 90 can be opened as will be hereinafter fully described.

The plate is provided with a central slot H through which extends a pin I' of a slide I which is mounted on the face of the plate 95 and said pin is secured in the body of a bolt member J' which is provided with spaced arms J² having heads J³ adapted to work within the notches of the tumblers when the tumblers are turned into such a position that they will register with the same and these heads are adapted to fit within the annular grooves D⁴ formed in the tumblers so that it will be impossible for the bolt member to be moved until the tumblers of 100 the respective shafts have been turned so as to aline with each other as it will be seen that when the heads of one pair of arms are in the grooves of the tumblers the opposite heads are against the tumblers.

Extending outwardly from the body of the sliding bolt member J' is a hook shaped

bolt J which is adapted to be moved by the slide eye over a slot G³ formed in the face plate G through which is adapted to extend the eye K of a hasp L and it will be seen that when the eye has been forced through the slot G³ and the tumblers have been turned so as to aline with each other by pushing on the slide I the bolt member can be moved in either direction so that the bolt 10 J can be moved in or out of the eye K of the hasp. The face plate G is preferably secured on the casing A by rivets as clearly shown and it is of course understood that various other ways can be employed for securing the plate in position.

The operation of the device is as follows: Supposing that the casing has been secured in position within the mortise of a door or trunk in such a position with respect 20 to the hasp that the eye will pass through the slot of the face plate of the casing, by operating the dials so as to bring the tumblers into such a position that the notches of the same will register, the bolt can be moved 25 on the face plate and after the bolt has been forced through the eye of the hasp by turning any one of the dials, the tumblers will be moved so that it will be impossible to open the lock until the combination has 30 again been worked so as to bring the tumblers in alinement and then by pushing on the slide I the bolt can be forced out of the eye so as to release the hasp.

From the foregoing description, it will be seen that I have provided a combination lock which is exceedingly simple and cheap in construction and one which is provided with four operating dials for operating the 35 respective tumblers which are so mounted with respect to the arms of the sliding bolt member that it will be necessary to turn all of the dials before the lock can be released and by operating any one of the dials the bolt can be locked.

Having thus fully described my invention, what I claim as new and desire to secure by Letters Patent, is:

1. The combination with a casing provided with a hasp receiving opening, of a hook bolt slidably mounted within the casing, adjacent said opening, arms carried by said bolt provided with heads at their ends, notched annularly grooved tumblers co-acting with said heads, dials for operating said tumblers and means for operating said bolt.

2. A lock comprising a casing provided with a bottom having slots formed therein,

shafts mounted in said casing, tumblers mounted on said shafts carrying dials extending through said slots, a face plate arranged on said casing provided with slots to receive said dials, a bolt slidably mounted on the under side of said face plate, headed arms carried by said bolt co-acting with said tumblers, and a member slidably mounted 60 on the face plate connected to said bolt for operating the same.

3. A lock comprising a casing provided with vertical dove-tailed shaped grooves in its ends, dove-tailed supporting blocks arranged in said grooves, shafts mounted in said blocks, notched tumblers mounted on said shafts, dials adjustably mounted on said tumblers, a face plate secured on said casing, a bolt member carried by said face 70 plate, arms extending outwardly from said bolt member provided with heads co-acting with said tumblers, and means for operating said bolt.

4. A lock comprising a casing having 80 spaced shafts detachably mounted therein provided with shoulders, notched tumblers provided with annular grooves arranged on said shaft against said shoulders, said tumblers being provided with disks having 85 toothed edges, dial rings provided with toothed portions co-acting with said disks, a face plate secured upon said casing, a bolt provided with spaced arms mounted under said face plate and coacting with said tumblers, and a slide mounted on said face plate 90 connected to said bolt.

5. A lock comprising a casing having dove-tailed shaped grooves formed in its ends, supporting blocks mounted in said 95 grooves provided with recesses, shafts mounted in said recesses provided with reduced portions, notched tumblers mounted on the reduced portions of said shafts provided with annular grooves, dials adjustably 100 mounted on said tumblers, a face plate secured upon said casing provided with slots to receive said dials, a bolt member slidably mounted on the under side of said face plate, arms extending outwardly from said bolt 105 member provided with heads adapted to fit within the annular grooves of the tumblers, and a slide mounted on said face plate connected to said bolt member for operating the same.

HARRIS HANFLIG.
